UNITED STATES PATENT OFFICE.

DAVID W. BRUNTON, OF LEADVILLE, COLORADO.

MINING-PUMP.

SPECIFICATION forming part of Letters Patent No. 255,928, dated April 4, 1882.

Application filed October 31, 1881. (No model.)

To all whom it may concern:

Be it known that I, DAVID W. BRUNTON, of Leadville, Colorado, have invented certain new and useful Improvements in Mining-
5 Pumps, of which the following is a specification.

My invention relates to improvements in mining-pumps used for the purpose of removing water from deep shafts; and the objects
10 of my invention are, first, to pump steadily with a less depth of water in the shaft than has heretofore been possible; second, to provide a means of draining the shaft should the lower valve become broken or injured and cov-
15 ered with water; third, to obtain the advantages of a telescope-section without increasing the suction-lift to a height which would interfere with the perfect working of the pump at the highest altitudes; and, fourth, to obvi-
20 ate the use of the cumbrous and expensive water-tanks at the pump-stations. I attain these objects by the mechanism illustrated in the accompanying drawing, in which—

a is the reciprocating rod of a series of Cor-
25 nish pumps.

m is the strainer to prevent chips and rocks from clogging the valve l.

k is a taper valve-seat, slightly smaller than the working-barrel S.

30 n is an auxiliary valve, which, in case of injury to the lower valve, l, can be dropped into the seat k, after the bucket-valve J has been drawn out of the working-barrel by removing the jack-head t.

35 P O is the delivery-pipe to the force-pump above.

h is the foundation on which the working-barrel b of the force-pump rests.

40 c is the plunger, and e and d the valves, of the force-pump.

f is the compensator to receive the amount of water displaced by the downward stroke of the bucket-rod i.

In the mining-pumps heretofore in use the
45 strainer has always been in the form of a hollow cylinder, and to obtain the required area of strainer-opening without weakening the cylinder it has been necessary to have the height of the perforated strainer about three times

50 the diameter of the suction-pipe, and, as the water can only be lowered by the pumps to the

level of the upper holes in the strainer, the depth of water in which men were compelled to work in the bottom of the shaft was, with a ten-inch pump, about thirty inches. Again, 55 the strainer-openings in the side of the cylinder have been necessarily horizontal, and soon became clogged with chips and rocks, hence requiring constant cleaning and attention. With my improved form of strainer m the 60 requisite area of strainer-opening can be obtained in a height for perforations of one and one-half diameter of the suction-pipe, and the strainer-openings incline downward at an angle of about forty-five degrees, and consequently free themselves from chips and small rocks each time the upward flow of water is stopped by the valve l.

Heretofore the seat for the auxiliary valve n has been placed in a tapered section of pipe 70 above the chamber of the valve l, thereby raising the auxiliary valve n to a height above the water which rendered it useless at high altitudes. By placing the taper seat k for the auxiliary valve n in the upper neck of the 75 chamber containing the valve l the distance from the valve-seat k to the water-level is reduced to a minimum.

Heretofore the telescope joint has been placed below the chamber of the valve l, and as the 80 shaft was deepened the strainer was lowered by sliding out the telescope-joint. This increased the distance between the valve l and the water-level to a height which rendered the pump almost useless whenever the upper 85 strainer-opening had admitted air. By my improved method of placing the telescope-slide u outside of the bucket-working barrel the distance between the working-barrel and the water-level is reduced to a minimum, and the 90 distance between the lower valve, l, and the water-level remains constant so far as affected by the extension of the telescope-slide.

Heretofore the water from the lift-pump has always been discharged into a tank on a level 95 with the force-pump, and from the water-tank the water is raised to the surface by force-pumps. The amount of cutting necessary to receive the tank's discharge and suction pipes weakens the shaft-timbering in a place where 100 the strength is most required—viz., at the foundation of the force-pump. In the draw-

ing the pumps are represented on the down-stroke. The force-pump plunger *c* is forcing the water from the plunger-barrel *b* through the valve *d* into the discharge pipe *x*. The weight of the column of water in the discharge-pipe *x* keeps the valve *e* firmly seated. As the force-pump plunger *c* and the bucket-rod *i* of the lift-pump are both rigidly connected to the reciprocating rod *a*, it follows that when the plunger *c* is descending into the working-barrel *b* and displacing a volume of water equal to its cubic contents through the valve *d* the bucket-rod *i* of the lift-pump is also acting as a smaller plunger, and forces a volume of water equal to its cubic contents through the pipe *P O* into the compensator *f*. By this my improved plan no cutting of the shaft-timbering is necessary, and the numerous bends in the water-pipe are avoided.

What I claim, and desire to secure by Letters Patent, is—

1. In a mining-pump, the telescopic extensible section *u*, in combination with and carrying at its lower end a conical strainer, *m*, of greater diameter than said pipe *u*, and provided with perforations opening downwardly, substantially as set forth. 25

2. In a mining-pump, the working-barrel *S*, provided with the reciprocating rod and bucket-valve *J*, in combination with the exterior telescopic slide, *u*, carrying valve *l* and strainer *m*, substantially as specified. 30

3. In a mining-pump mechanism, the force-pump *b c* and a lift-pump below said force-pump, in combination with the connecting-pipe *O* and compensating-pipe *f*, all constructed, arranged, and operated as set forth. 35

DAVID W. BRUNTON.
